UNITED STATES PATENT OFFICE

162,377

CALCULATING MACHINE CASING

Robert D. Budlong, Skokie, Ill., assignor to Victor
Adding Machine Co., Chicago, Ill., a corporation
of Illinois

Application July 1, 1950, Serial No. 10,926

Term of patent 14 years

(Cl. D64—11)

To all whom it may concern:

Be it known that I, Robert D. Budlong, a citizen of the United States, residing at Skokie, in the county of Cook and State of Illinois, have invented a new, original, and ornamental Design for a Calculating Machine Casing, of which the following is a specification, reference being had to the accompanying drawings forming part thereof.

Fig. 1 is a side elevational view of a calculating machine casing, showing my new design;

Fig. 2 is a plan view;

Fig. 3 is a front elevational view; and

Fig. 4 is a rear elevational view.

I claim:

The ornamental design for a calculating machine casing, substantially as shown.

ROBERT D. BUDLONG.
